Original application August 6, 1941, Serial No.
405,724. Divided and this application February
1, 1943, Serial No. 474,412

5 Claims. (Cl. 104—10)

Our invention relates to an electromagnetic motor and has particular reference to a long stroke electromagnetic reciprocating tool finding particular utility when employed as a soil tamper or like device.

This application is a division of our copending application Serial No. 405,724, filed August 6, 1941, and entitled "Electromagnetic motor."

Many attempts have been made prior to our invention to construct a compact and efficient reciprocating electromagnetic motor, but these attempts have not been entirely successful in that the devices were heavy, operated at low efficiency and were incapable of delivering large outputs of power without destructive overheating.

The prior devices also were unsuited for use as soil tampers because they could not produce a sufficiently long stroke to effect an adequate tamping of the soil and were, by virtue of their short stroke characteristic, limited in their application to percussion tools, such as hammers, chisels, breakers, rock drills and the like.

The present invention is directed to the provision of an electromagnetic motor of the character above discussed and it is an object of our invention to provide a motor which overcomes the above noted disadvantages and which is relatively compact and efficient in operation.

It is also an object of our invention to provide an electromagnetic motor of the reciprocating type employing a plunger which is reciprocated by the alternate energization of opposed electromagnets.

It is an additional object of our invention to provide a motor of the character set forth in the preceding paragraphs in which a novel form of electromagnet winding is employed to reduce the self-inductance of the coil to thereby increase the speed of action of the motor and to provide for a higher operating efficiency than has been hitherto possible to reduce the size and weight of the device.

It is a still further object of our invention to provide an electromagnetic soil tamping device in which the soil engaging tamping foot is secured to the plunger of a reciprocating electromagnetic motor to be reciprocated therewith.

It is also an object of our invention to provide a soil tamping device of the character set forth in the preceding paragraphs in which the stationary opposed electromagnets are mounted for longitudinal movement independently of each other.

It is additionally an object of our invention to

provide a soil tamping device of the character set forth hereinbefore which includes a positive stop means for limiting the movement of the electromagnets toward each other and a resilient stop for yieldably limiting the movement of the magnets away from each other.

Other objects and advantages of our invention will be apparent from a study of the following specification, read in connection with the accompanying drawing, wherein

Fig. 1 is a perspective view illustrating the electromagnetic motor of our invention as embodied in a soil tamping mechanism;

Fig. 2 is an enlarged elevational view of the mechanism illustrated in Fig. 1 with parts broken away and other parts shown in section to illustrate the details of construction;

Fig. 3 is an elevational view similar to Fig. 2 but taken in a direction at right angles to the direction of the view in Fig. 2; and

Fig. 4 is a cross sectional view taken substantially along the line IV—IV of Figs. 2 and 3.

Referring to the drawing, we have illustrated in Fig. 1 a soil tamping mechanism which is powered by means of an electromagnetic motor constructed in accordance with the preferred embodiment of our invention. The mechanism illustrated in Fig. 1 comprises opposed upper and lower electromagnet structures 1 and 2 which are supported in a manner to be described hereinafter within a stationary frame structure 3 fitted with handles 4 or other suitable appurtenances for holding and supporting the device while in operation. The magnets 1 and 2 are adapted to cause reciprocation of a plunger 5 to which is permanently secured a supporting structure 6 carrying at its lower end a tamping foot structure 7.

The tamping foot 7 preferably comprises a plurality of short parallelly extending bars 8 interconnected as by means of a cross tie member 9 to which the connecting device 6 is secured. Each of the bar members 8 has preferably a trapezoidal cross section, being characterized particularly by upwardly and outwardly sloping side walls 10 defining a relatively small flat undersurface 11. This form of tamping foot is preferred to the older forms of tamping feet previously employed and characterized by presenting a large surface area to the soil to be tamped because the large area devices served to tamp, compact and harden only the upper layer of soil being tamped, with the result that there was produced merely a hard crust upon the surface,

whereas the tamping foot of the character above described penetrates below the surface of the soil being tamped and effects a compacting of the soil from the bottom up so that when the tamping operation is completed, the entire body of soil is suitably compacted.

Each of the stationary electromagnet structures 1 and 2 is preferably constructed as illustrated in detail in Fig. 2 and includes a substantially cylindrical shell portion 12 of a suitable magnetic material internally bored as indicated at 13 to provide a cylindrical recess within which an electromagnet coil 14 is received. The coil 14 is preferably wound upon a spool consisting of an inner cylindrical spool shank 15 formed of a suitable non-magnetic material and carrying spool end flanges 16 and 17 formed of a suitable insulating material such as fiber, Bakelite, or similar substance.

In winding the magnet 14, there is preferably first wound an innermost layer 18 of insulating material such as glass tape, mica-paper or asbestos tape (a preference being expressed for those insulating materials capable of withstanding relatively high temperatures). Upon the spool shank 15 there is then wound a plurality of independent coaxial multi-layer solenoid coils 19, each of the coils 19 being insulated from adjacent coils as by means of interposed layers 20 of a heat-resistant insulating material.

Exteriorly of the spool ends 16 and 17 we position inner and outer terminal rings 21 and 22 suitably insulated from the coil 14 and from the magnet structure 12 as by means of insulating material 23. Like terminals of each of the coils 19 are connected by conductors to the ring 21, for example, and the opposite like terminals of the coils are connected by means of conductors to the ring 22. Thus the rings 21 and 22 comprise input and output terminals, respectively, for all of the individual coils 19, which coils are connected in parallel between such input and output terminals.

By employing a plurality of solenoid coils 19 mounted coaxially with respect to each other and connected in parallel in the manner above described, we have been able to provide a solenoid capable of producing a relatively large magnetomotive force which is characterized by having a relatively low self-inductance. It is important to keep the self-inductance of the coil as low as possible since the speed of action of the electromagnetic motor is limited primarily by the self-inductance of the coil. Furthermore, coils having a high self-inductance cause burning and rapid destruction of the contacts which are employed to energize and de-energize the coils.

After the coil is assembled, it is preferably impregnated with cement or other impregnating material having the property of withstanding relatively high temperatures and having reasonably high heat conductivity. One such impregnating material which we have found to be eminently satisfactory consists of a mixture of extremely fine sand and "Luminite" cement with water, which mixture after impregnation sets to form a hard, solid and mechanically strong one-piece structure. Luminite is a special Portland type cement manufactured by the Atlas Cement Company and characterized particularly by having an extremely low shrinkage and rapid setting characteristic.

The coil structure thus formed is retained within the cylindrical recess 13 as by means of a cover 75

plate 24 which is suitably secured to the outer ends of the magnet shells 12.

The interior bore of the spool shank 15 serves as a guiding bore for receiving a cylindrical portion 25 of the plunger 5. The end of the cylindrical portion 25 is preferably provided with a conical or tapered form indicated at 26 to coact with a similarly tapered cone-shaped recess 27 formed in the innermost end of a fixed stop member 28 formed by preference integrally with the end cap member 24. Upon energization of the solenoid coil 14, the plunger is drawn upwardly to bring the conical end 26 into engagement with the conical recess 27.

Magnetic sticking of the plunger to the stop member 28 may be avoided by lining the conical recess 27 with a thin layer 29 of non-magnetic material such as manganese steel or other suitable alloy having the requisite strength and hardness. Cushioning of the plunger or resistance to upward movement of the plunger resulting from air being trapped in the conical recess 27 may be avoided by providing a breather opening 30 extending into communication with the exterior of the magnet structure.

The lower portion of the magnet shell 5 is preferably formed of considerable thickness and provided with a tapered throat portion or entrance aperture 31 which is adapted to coact with a similarly tapered portion 32 of the plunger 5. The plunger 5 is enlarged at its central portion as indicated at 33 to provide a pair of the tapered conical portions 32 which extend in opposite directions from the enlargement 33.

The lower end of the plunger 5 is preferably identical in form and shape to the upper end which is illustrated in Fig. 2 and the lower magnet structure 2 is preferably identical in construction with the magnet structure 1 above described.

At this point attention is particularly directed to the enlarged central portion 33 of the plunger 5, the coned sections 32 adjacent thereto, and the similarly coned throat portion 31 which is provided on each of the magnet structures 1 and 2.

By forming the surfaces 31-32 and 26-27 as cones rather than as radially extending plane surfaces, a much longer stroke is permissible without producing an excessive air gap between the plunger and the component parts of the magnetic circuit formed by the stop member 28, the shell 12 and the throat portion 31. This long stroke characteristic is of particular utility when the motor is employed as a tamping device.

The magnet structures 1 and 2 previously referred to are identical in construction and supported independently of each other within the supporting frame 3.

The supporting frame 3 preferably comprises a pair of parallelly extending rail members 34 and 35 closely embracing the sides of the magnet structures 1 and 2 and being interconnected at opposite ends by means of cross pieces 36 and 37. The members 34-37 may conveniently be formed integrally with each other. The magnet structures 1 and 2 are slidably supported between the rail members 34 and 35 as by securing to each of the magnet structures a pair of longitudinally extending cleat members 38 and 39 defining guiding channels within which the rail members 34 and 35 are received. Movement of the magnet structures 1 and 2 away from each other is preferably yieldably limited by means of

compression springs 40 and 41 interposed be-

tween the magnet unit 1 and cross piece 36 and between the magnet unit 2 and cross piece 37, respectively. Movement of the magnet structures 1 and 2 toward each other is preferably limited by means of positive stop members 42 and 43 which may conveniently comprise cleats suitably secured as by welding to the inner surface of each of the rail members 34 and 35 and disposed in a position to be engaged by the adjacent ends of the magnet structures 1 and 2.

The connecting member 6, which serves to interconnect the plunger 5 and the tamping foot 7, may conveniently comprise a pair of longitudinally extending members 44 and 45 disposed on opposite sides of the lower magnet structure 2 and having inwardly turned upper ends 46 and 47 which may be permanently secured as by welding 48 to the enlarged central portion 33 of the plunger 5. The lower ends of the members 44 and 45 are preferably turned inwardly toward each other, as indicated at 49 and 50, to abut the cross tie member 9 to which the ends 49 and 50 are suitably secured as by welding.

The magnet structures 1 and 2 are alternately energized and de-energized by any suitable switching device connected between a suitable source of electrical energy and the coils 14 to effect a reciprocation of the plunger 5. By virtue of the connecting means 6, the tamping foot 7 is caused to reciprocate with the plunger 5 so that the foot 7 may be caused to repeatedly strike tamping blows against soil to be tamped to thereby effect a tamping and compacting thereof in the manner previously described.

It will be noted from the foregoing that the plunger is permitted unlimited upward movement upon energization of the upper magnet structure 1 with the result that the upper end of the plunger will engage the upper stop 28. This serves to divide the momentum of the plunger between the plunger and the upper magnet structure 1, causing an upward sliding movement of the magnet structure 1 within the supporting frame 3 and resulting in a compression of the spring 40. Upon de-energization of the upper magnet 1 and the energization of the lower magnet 2, the energy stored in the spring 40 will return the upper magnet structure 1 to a position engaging the stops 42 and 43 and will thus serve to produce an initial downward acceleration of the plunger 5, assisting the tractive effort produced by the energization of the lower magnet 2. Thus, the tamping blow which is struck by the tamping foot is more severe than would be normally expected since the energy for producing that blow is derived in part from the upper magnet structure 1 as well as from the lower magnet structure 2.

Ordinarily the supporting frame 3 is so positioned that the energy of the tamping blow is expended before the plunger engages the lower stop member carried by the lower magnet assembly 2, but this structure is also slidably supported within the frame 3 by the lower spring 41 to permit the shock of the plunger striking the lower stop member to be absorbed in case the supporting frame 3 is elevated to a sufficient height to prevent the tamping foot 7 from engaging the soil.

From the foregoing it will be observed that we have provided a novel form of reciprocating electromagnetic motor which is characterized particularly by employing a novel magnet construction resulting in a low self-inductance of the solenoid employed and permitting the solenoid to be operated with higher efficiency than has been hitherto

possible. Furthermore, the use of the cement or similar hardening, impregnating material hereinbefore described permits the solenoid coils to successfully withstand the shocks and jars resulting from the operation of the device.

Attention is directed to the fact that the novel magnet construction herein described provides for a relatively long plunger stroke, thus adapting the motor for use with a soil tamping device of the character herein described wherein the magnet units are each separately mounted and provided with resilient stop members permitting at least a portion of the previously wasted up-stroke energy to be added to the energy produced on the down-stroke to thus produce a stronger and more effective tamping blow.

While we have shown and described the preferred embodiment of our invention, we do not desire to be limited to any of the details of construction shown or described herein, except as defined in the appended claims.

We claim:

1. In a solenoid for use with reciprocating electromagnetic motors, the combination of: a tubular coil spool shank; a plurality of concentrically disposed and radially aligned multi-layer solenoid coils surrounding said shank; a pair of annular terminal members surrounding said shank and positioned at opposite ends of said coils, said members each having an outside diameter substantially equal to the outside diameter of said coils; securing means for attaching said terminal members to said coils in electrically insulated relation thereto; means connecting the inner end of each of said coils to one of said terminal members; and means connecting the outer ends of each of said coils to the other of said terminal members.

2. In a soil tamping device, the combination of: a reciprocal plunger; a tamping element connected to said plunger for movement therewith; a pair of opposed magnet structures for reciprocating said plunger; and means mounting said structures in axial alignment with each other and for independent axial movement.

3. In a soil tamping device, the combination of: a reciprocal plunger; a tamping element connected to said plunger for movement therewith; a pair of opposed magnet structures for reciprocating said plunger; means mounting said structure in axial alignment with each other and for independent axial movement; and positive stop means for limiting the movement of each of said structures toward the other.

4. In a soil tamping device, the combination of: a reciprocal plunger; a tamping element connected to said plunger for movement therewith; a pair of opposed magnet structures for reciprocating said plunger; means mounting said structure in axial alignment with each other and for independent axial movement; positive stop means for limiting the movement of each of said structures toward the other; and resilient stop means for yieldably limiting the movement of each of said structures away from the other.

5. In a soil tamping device, the combination of: a reciprocal plunger; a tamping element connected to said plunger for movement therewith; a pair of opposed magnet structures for reciprocating said plunger; a supporting frame for said structures including a pair of parallelly disposed rail members extending longitudinally on opposite sides of said structures and having corresponding ends interconnected by cross tie mem-

bers; means mounting each of said structures for independent longitudinal sliding movement along said rail members comprising longitudinal cleats secured to each of said structures on opposite sides of each of said rail members to define guides receiving said rail members; a stop carried by said rail members in a position to be engaged by each of said structures upon movement thereof toward the other structure to a predetermined position;

and a compression spring interposed between each of said structures and the cross tie member adjacent thereto.
